UNITED STATES PATENT OFFICE

GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY

BOX AND SUPPORT

Application filed February 7, 1928. Serial No. 252,435.

This invention relates to electrical outlet boxes and supports and particularly to box supports for use in connection with electrical house-wiring work, and the box and support is designed to be anchored to a hanger rod so as to carry a lighting fixture from the box and hence from the hanger rod, the latter being anchored to the wall or ceiling of the building in any approved manner.

10 An object of the invention is to produce a novel combination box and support which are adjustable laterally along the hanger rod so as to properly locate the lighting fixture when the latter is attached to the box and suspended 15 from the ceiling or extended outwardly from the wall.

A further object is to produce a combination improved outlet box and support therefor capable of being mounted and carried on a 20 rod, and to this end I have produced a novel type of box construction which readily receives a box support thereinto, and means are provided to clamp the box and support on the hanger rod and conceal from the rear of the 25 box the wiring at the front of the box.

20 A further object is to produce a combination box and support which locks or anchors against turning movement after the same is mounted on the hanger rod and the device 30 therefore provides a rugged and durable construction against which a mechanic may work and twist when he is installing a lighting fixture.

Having the above and other objects in view, 35 reference is now made to the views in the accompanying drawings which illustrate an example of the invention, the form of which may be varied in certain particulars without departing from the principle of the invention.

Figure 1 shows the box and support in plan view looking down on top or at the rear face thereof with a portion of a support member, 45 in the form of a box cover support plate, broken away and showing the hanger rod clamped between the box and support. One cable is also shown inserted in the box.

Figure 2 shows a lengthwise section on the 50 line 2-2 of Figure 1, which affords a side

elevation of the hanger rod and a section of the box and its cover support plate.

Figure 3 shows a cross section on the line 3-3 of Figure 1, which affords a partial cross section and partial side elevation of the box 55 and cover support plate and cuts across the hanger rod showing the latter clamped to the box by the cover support plate.

Figure 4 shows a perspective view of the box and support with the parts disposed in 60 separated alignment ready to be placed together.

Figure 5 is a cross section on the line 5-5 of Figure 1 to fully show a cable opening or socket formed in the box and wire bushings 65 at the lower part of the socket and out through which the wire of a cable passes.

Figure 6 is a cross section through the support member shown for example as a disc or cover plate to enclose the rear face of the 70 box.

In house and building electrical wiring installations, outlet boxes B are used for establishing cable and wire terminals. The cable C is anchored to the box B and the 75 cable wires W hang free from the box ready to make electrical connection with the wires of an electric fixture or other device, not shown. Various connector means are employed for anchoring the cable C to the box 80 B. Likewise it is necessary to provide means, such as a box support, to attach the box to the building, say to the ceiling or to the wall, and my invention relates to the latter improvements wherein I produce a box and 85 support especially designed to be carried on a hanger rod R having holes in the outer ends thereof by which the rod is fastened to studs or joists in the building.

My invention relates in particular to a box 90 support, or it may be called an outlet box and support, and I have devised a new form of box which is adapted to fit onto the hanger rod R. I have also devised a box support having a clamping function which anchors 95 the box against movement on the rod R, the support serving other uses such as covering the rear face of the box, and also carrying knock-outs through which a cable C is led into the box.

The form of box member B which I use to illustrate the invention may comprise a cast box having a rim 8 integral with a web 9. A lighting fixture support or stud 10 may also be formed integrally with the web 9. 5 The tubular stud 10 is usually screw threaded for the reception of a hickey or other means of attachment with the lighting fixture or other electrical device. The stud 10 depends centrally from the box and affords means to receive and carry the weight of a lighting fixture adapted to be supported on the building wall from the rod R.

The rim 8 in fact extends beyond or to either side of the web 9 so as to form an upper rim 12. The box rim 8-12 may be considered one and the same portion with the box web 9 disposed substantially in the center thereof and transversely of the axis of the stud 10 and rim 8-12. A pair of upstanding flanges 14 are formed in the upper portion of the box within the rim 8-12 and are spaced apart, the stud 10 being centrally disposed between these upstanding flanges 14. Each upstanding flange 14 defines therein one wall of a cable socket or opening 15 leading downwardly into the box and terminating at the lower extremity thereof in one or more, in this instance two, bushed wire 30 passages 16. The box rim 8-12 defines the other wall of the cable socket 15. A pair of cable sockets 15 are therefore shown, and they may be arranged in any relation to the other box portion but they are here shown as being 35 diametrically opposite each other. The cable openings 15 may be formed oblong as shown and two cables may therefore be readily introduced into each socket opening 15.

Cable and box connector or anchorage 40 means is employed to fasten a cable C in each cable socket 15. The cable connector or clamp here employed comprises a single cable clamp screw 17 threaded through the box rim 8-12 so that the threaded end of 45 the screw projects into the socket 15, the screw being mounted substantially parallel to the box web 9 if desired. A screw 17 may therefore be used to anchor two cables in the box and when so anchored the cable C has 50 its lower end seated on the bushing 16 and the wire W passes therethrough and is free for connection with the other wires leading from a lighting fixture not shown.

The upper or rear face box rim portion 12 55 is notched at diametrically opposite points as indicated at 19. The two rim notches 19 and the two upstanding flanges 14 taken together define a rod passage, channel or rod seat 19 through the box and into which the 60 rod R is seated. This rod channel 19 affords room for the rod R to fit down into the rear face of the box. A clamp or box support cover device anchors the box to the rod R as will be explained. The upstanding flanges 65 14 preferably are made less in height than the

thickness of the rod R, as shown in Figure 3 and other views. The rod R therefore rests in the notched rod seat or channel 19 and the upper surface of the rod R is slightly above the upper surface of the socket and rod seat 70 forming flanges 14.

A box support device in the form of a box cover plate 21 preferably is made circular to fit the upper portion of the box and within the box rim 12 and is adapted to rest upon the rod R. This support plate 21 fits freely into the box rim 12 and engages the hanger rod R since the upstanding flanges 14 do not reach to the upper surface of the rod R and hence do not support the plate 21. Tapped screw holes 22 are made in the plate 21 and box support screws or operating means 23 are passed freely through screw holes 24 made in the box web 9, one hole 24 being placed to each side of the rod R. The box support screws 23 are screw threaded into the tapped holes 22 in the cover support 21. 80

By tightening the box support operating screws 23, it follows that the box support plate 21 and the box member B are both 90 clamped tightly together on the rod R. Before tightening the box support screws 23, the box member B may be shifted or adjusted on the rod to the right position so as to properly locate the lighting fixture subsequently attached to the box stud 10.

The box support device 21 is advantageously made in the form of a cover plate so as to conceal the wiring in the box from the rear or upper side thereof. The other side of the box or its front face is usually covered by a canopy or other ornamental means not shown since the same has no relation to this invention. The box support cover plate 21 is made with knock-outs 26 which simply comprises a tool marking punch delivered against the cover 21 to mark and outline the knock-out disc 26 in the cover 21 thereby leaving a box hole H leading directly into the cable socket 15. Ordinarily one cable C is anchored to the box and only one knock-out disc 26 is required to be knocked out of the plate 21, so the box cover 21 is left intact and conceals the rear face of the box so that the electrical connections made with the wires W at the front of the box are not exposed from the rear of the box, which is an advantage. 105

The form of box described provides means 120 for attaching a plurality of cables with a minimum number of clamp screws 17, and another advantage resides in the fact that the box support 21 is itself a cover which conceals the wires and not only that, but the 125 cover carries the knock-out openings to admit entry of the cable C into the box. Furthermore the cover acts as a clamp to anchor the box to the hanger rod R, the latter being securely clamped between the box web 9 and 130

the cover plate 21 when the operating screw means 23 are tightened up.

I have therefore produced a box and box support combination which includes a cast 5 box member B having a hanger rod receiving means such as a seat, together with the rod R, the plate or disc 21 acting as a cover and providing knock-out openings or cable holes H through which a cable is led to and seated 10 in the cable socket 15. The flanges pointed out at 14 extend downwardly through the box web 9 to give depth to the cable sockets 15.

It is significant that the rear face of the 15 casting or box member B under the cover 21 is flat and open where the rod R is received, i.e., the box casting has an open rear face into which is received and against which the rod is placed. Therefore, the box is easily fitted 20 against the rod, the latter resting in the notches 19 and in the seat defined by these notches and by the upstanding flanges 14. The rod R rests between the flanges 14 and in contact with the rear face of the box web 25 9 and the box is therefore securely anchored to the rod by the cover.

The flanges 14 perform the several functions of locking the box against rotation, of extending downwardly through the web 9 30 to define the deep cable sockets 15, and of strengthening the box. The box support screws or clamp operating means 23, and the cable clamp screws or cable anchorage means 17 are easily accessible for tightening and 35 loosening operations so that the box is simple to install. The structure is neat in appearance and assembly since the rod R fits into the box and is concealed by the support and cover plate 21.

40 While I have in fact mentioned that the upstanding flanges 14 secure the box against rotation, it is quite evident that the rim-notched means 19 also largely contribute to this function. Its two notches 19 are formed 45 along a line drawn midway between that position of the flanges which are on the same side of the web with the notches. Furthermore the flanges 14 terminate at the rim and integrally join this marginal rim 8—12 carried by the web 9 so that the cable openings 50 15, being bound or surrounded by the flanges 14, are in fact formed into the cable sockets 15.

What is claimed is:

55 1. A box and support comprising; a box member including a cable socket into which a cable is received, and having an open rear face, means forming a rod seat in the open rear face, and a fixture stud carried with 60 the box member; cable anchorage means to fix a cable in the socket; a box supporting device mounted on the rear face of the box member and including a cover fitted over said open rear face to cover the cable socket, and 65 being provided with a knock-out opening

through which a cable is led into said socket; and means for drawing the supporting device and box member together and adapted to clamp a hanger rod therebetween.

2. A box support comprising, a casting 70 made with a threaded stud adapted to receive and support a lighting fixture, said casting being provided with a cable receiving opening into which a cable is inserted, cable anchorage means carried with the casting to fix the cable in the opening, said casting being provided with a rim having oppositely formed notched means to receive a support rod thereinto and lock the casting against rotation, a supporting device including a cover 80 plate having a cable passage therethrough disposed within the rim and over the means in which the rod is seated, and operating means carried with the casting engaging the supporting device and acting to clamp the device against the rod and clamp the casting 85 against the rod.

3. A box and support comprising; a box member including, a rim and a web integrally within the rim, a fixture stud integral with the web, said member having a cable receiving socket, and also having a rod receiving means formed by notches made in the rim; cable anchorage means carried with the member to fix a cable in the socket; a box cover having a cable passage therethrough placed over the member to close the rod receiving means and to close the cable receiving socket; and operating means carried on the member reaching through the web and engaging the 90 box cover to clamp the latter against a rod mounted in the rod receiving means. 100

4. A box and support comprising, a member formed with a web and rim, said rim made with oppositely disposed notches affording a space into which a hanger rod is adapted to be received and seated against the web, a flange on the web joining the rim and defining a cable receiving socket, a screw threaded through the rim into the socket to fix a cable therein, a cover plate having a cable passage therethrough mounted on the box over the space into which a hanger rod is received and mounted over the socket, and screws mounted through the web and screw- 110 threaded into the cover plate. 115

5. A box and support comprising, a box including a web bounded by a rim, said web being provided with cable openings, flanges formed around the cable openings to provide cable sockets and the flanges being connected with the rim, said rim being notched at opposite points along a line between the cable sockets to receive a hanger rod and seat the latter on the web between the sockets, a box support cover mounted on the box over the cable opening and having knock-outs, a screw which is threaded through the rim into each socket to grip a cable, and screws extended 120 125 130

through the web and which are threaded into the cover to clamp the latter on the box.

6. A box and support comprising, a box member including a web formed with spaced cable openings, flanged means surrounding each opening thereby producing cable sockets, screws threaded through the flanged means into each socket to fix a cable therein, said sockets being spaced apart to form a space into which a hanger rod is adapted to be received, a cover having a cable passage therethrough placed over the sockets and spreading across the space in which a hanger rod is received, and screws to clamp together the cover and box.

7. A box comprising, a box member including a web through which a pair of cable openings are formed, a flange surrounding each opening, a screw which is threaded through each flange into the opening to grip a cable therein placed, said cable openings and surrounding flanges being separated to afford a space therebetween to receive a hanger rod adapted to be seated on the web, a cover plate mounted on the box over the space and including knock-outs proximate the cable openings through which a cable extends into the box, and screws extended through the web into the cover plate to clamp the box to the latter.

8. An outlet box comprising, a member provided with two cable openings spaced apart and adapted to have a hanger rod placed against the member between the two cable openings, a rim extending around the member, means carried by the rim to fix a cable in the openings, said rim being notched at opposite points to afford a space to receive the rod aforesaid through the rim, a cover plate having knock-outs and being mounted on the member over the space adapted to be occupied by a rod, and a screw extended through the member on either side of the space and hence a hanger rod and threaded into the cover plate to clamp the box to the plate.

9. A box and support comprising a box member, a fixture support carried by the box member, a cable opening in said member, a hanger rod, means to clamp the box member to the hanger rod and to cover the cable opening, and a knockout opening in said means.

10. A box and support comprising a box member, a fixture support carried by the box member, a cable socket in said member, a hanger rod, means to clamp the box member to the hanger rod and to cover the cable socket, and at least one knockout opening in said means.

11. A box and support comprising a cast box member, a fixture support integral therewith, a cable opening in said member, a hanger rod, means to clamp the box member to the hanger rod and to cover the cable

opening, and a knockout opening in said means.

12. A box and support comprising a cast box member, a fixture support integral therewith, a cable socket in said member, a hanger rod, means to clamp the box member to the hanger rod and to cover the cable socket, and at least one knockout opening in said means.

13. A box and support comprising a box member having an open rear face, a fixture support carried with the member, a cable passage through the member from the open rear face, a hanger rod, a cover plate covering the open rear face and to clamp the hanger rod to the member, and a knockout hole in the cover plate.

14. A box and support comprising a box member having an open rear face, a fixture support carried with the member, a cable passage through the member from the open rear face, a support for the box member, a cover plate covering the open rear face and to clamp the support to the box member, and at least one knockout hole in the cover plate.

In testimony whereof I affix my signature. 90
GEORGE C. THOMAS, JR.
